UNITED STATES PATENT OFFICE.

WILLIAM McGEE YOUNG AND RUSSEL SUTHERLAND SMART, OF OTTAWA, ONTARIO,
CANADA.

VALVE FOR INTERNAL-COMBUSTION ENGINES.

1,176,418.

Specification of Letters Patent.

Patented Mar. 21, 1916.

Application filed October 15, 1910. Serial No. 587,329.

To all whom it may concern:

Be it known that we, WILLIAM McGEE YOUNG and RUSSEL SUTHERLAND SMART, both of the city of Ottawa, in the Province of Ontario, Dominion of Canada, have invented certain new and useful Improvements in Valves for Internal-Combustion Engines, of which the following is a specification.

Our invention relates to improvements in valves for internal combustion engines and the like, and the objects of our invention are to provide a simple and effective form of valve mechanism operable without noise and a minimum amount of friction and which 10 may be readily lubricated and water cooled to avoid excessive heating.

Further objects are to enable both ports to be controlled by a single valve member, whereby, the number of rotating parts will 20 be reduced and the valve mechanism very much simplified.

Further objects are to provide means for securing a quick cut-off for both ports.

Further objects still are to prevent leakage of the valve joint between the valve member and the engine cylinder.

In its construction the invention includes a tubular valve member or members mounted on the interior of the engine cylinder and 30 adapted to be turned to different positions to control the exhaust and inlet ports. In one form of the invention, a single valve member is arranged to control both ports, the movement of the member in one direction being adapted to open one port, while 35 the movement in the opposite direction opens the other port. In this form of the invention, means are provided for imparting a reciprocative movement to the valve in opposite directions, with a quick return motion. Separate valve members may be provided for each of the ports if desired. In 40 order to minimize space, a portion of the valve member, or one of the valve members 45 is arranged to occupy a cylindrical recess in the end of the cylinder, which also forms a compression space for the explosive mixture. Leakage between the valve member and the cylinder may be conveniently controlled by means of a ring located in a 50 groove formed in the edge of the valve member and normally spring pressed outwardly. These and other details of the invention are more fully set forth and described in de-

tail in the accompanying specification and 55 drawings.

In the drawings: Figure 1 is a vertical section through the end of an engine cylinder embodying the present invention. Fig. 2 is a plan view of the end of the cylinder. 60 Fig. 3 is a perspective view showing the operative mechanism for the valve, said view being partially in section. Fig. 4 is a section on the line 2—2, Fig. 1. Fig. 5 is a section on the line 3—3, Fig. 1. Fig. 6 is a sectional 65 view of the end of the cylinder embodying an alternative form of the present invention. Fig. 7 is a section on the line 4—4, Fig. 6. Fig. 8 is a section on the line 5—5, Fig. 6. Fig. 9 is an enlarged sectional detail through 70 the connection between the valve member controlling the exhaust port and the engine cylinder. Fig. 10 is a plan view of the top of the cylinder of the form shown in Fig. 6. Fig. 11 is an enlarged detail view showing 75 the valve packing.

In the drawings like characters of reference indicate corresponding parts in each figure.

Referring first to the embodiment of the 80 invention illustrated in Figs. 1 to 5, G represents a cylinder of the usual water cooled type. a and a' represent the exhaust ports which open near the end of the cylinder and are circumferentially and diametrically opposite to each other. b and b' represent the inlet ports which are located in the end of the cylinder and open into a cylindrical recess b² adapted to form a compression space 85 at the end of the cylinder. H represents the valve member which is tubular in form and fitting closely to the inside of the cylinder, the latter conveniently having a seat h on which the valve is mounted. Where a seat such as this is employed, it would facilitate 90 the introduction of the valve member if the head G' of the cylinder was formed separately of the body portion thereof. It will be seen that the valve member H is formed with an inner-section h' of larger diameter 95 and controlling the exhaust ports, and an outer-section h² of less diameter fitting closely to the cylindrical recess b² and controlling the inlet ports. Apertures are formed in the valve member in such a manner that 100 when the member is turned in one direction it will open the inlet ports, and when turned 105 in the opposite direction it will open the ex-

haust ports. Thus diametrically opposite apertures or slots h^3 and h^4 are provided in the section h^2 , adapted in a certain position to register with the inlet ports. The section 5 h' is also provided with apertures or slots h^5 and h^6 adapted in a given position to register with the exhaust ports a and a' . When the valve member is in closed position, the ports h^5 and h^6 lie on the opposite side 10 with respect to the exhaust ports to that on which the apertures h^3 and h^4 lie with respect to the inlet ports. The valve member is substantially co-axial with the cylinder and being near the periphery thereof may 15 be readily lubricated by any well known means and will obtain the benefit of the water cooling of the cylinder. To prevent leakage between the valve member and its seat, a ring h^7 may be provided extending in 20 grooves h^8 and h^9 in the valve member and cylinder respectively, and normally spring pressed outwardly by suitable spring h^{10} . The valve member may have a reciprocative 25 turning movement imparted thereto by any suitable mechanism, preferably of such a character as to impart a quick return motion which will effect a quick cut-off of both exhaust and inlet ports. In the embodiment 30 illustrated, a spindle I is connected to the valve member and extends through the end of the cylinder, a lever i being provided on the end of the spindle, and held in normal 35 position by means of tension springs i^1 and i^2 which are connected thereto and diverge therefrom to opposite sides where they are 40 connected to the top of the cylinder, the tendency of said springs being to quickly return the lever to normal position when moved therefrom. The lever is adapted to 45 be moved alternately to opposite sides and then released, by means of a reciprocative tappet member J . This tappet member 50 which reciprocates in guides j on the top of the cylinder, carries three tappet projections j^1 , j^2 , and j^3 , the center one of which is 55 adapted in normal closed position of the valve member, to engage one side of the lever i . On reciprocation of the member, the projection j^2 is adapted to engage the 60 end of the lever i and swing the lever to one side and ultimately release it, permitting it to swing back under the action of the spring. The projections j^1 and j^3 will prevent oscillation 65 of the lever after return to normal position, for by the time the projection j^2 moves sufficiently to release the end of the lever, either the projection j^1 or j^3 will be in position near the center of the lever and stop it immediately it comes to its central normal 70 position. For this purpose, any of the well known valve mechanisms for four-cycle explosive engines might be used. The member J may reciprocate in any suitable way from the engine shaft. By way of illustration, 75 we have shown a simple mechanism for per-

forming this function comprising a bell-crank j^4 pivoted to the engine cylinder and having one arm connected to the frame and the other arm connected to a longitudinally movable rod which is spring pressed downwardly by means of a spring j^6 engaging a support j^7 for the rod and a collar j^8 on the rod, the end of the rod carrying a roller j^9 running on a cam j^{10} which is rotated from the main engine cylinder, as for example by means of a subsidiary crank shaft j^{11} carrying the cam and rotated by a chain j^{12} and sprockets j^{13} and j^{14} on the auxiliary and main shaft respectively.

In the operation of the mechanism, when the member J is reciprocated in one direction, it will swing the lever i carrying the valve member H until the apertures h^4 and h^5 register with the inlet ports b and b' , permitting the inflow of the motive fluid. On the motion being continued, the tappet projection j^2 will pass the end of the lever i , which under action of the spring will return quickly to normal position, shutting off the inlet port. The mixture will then be compressed and ignited, during which time the reciprocative member will return to normal position and the projection j^2 will engage the opposite side of the lever i to that which it previously engaged. The motion being 95 further continued, the lever i will be swung to the opposite side, turning the member H in the opposite direction, and bring the apertures h^5 and h^6 into registration with the exhaust ports a and a' , permitting exhaust 100 of the motive fluid. This action will be repeated during the operation of the engine.

In the alternative form of the invention shown in Figs. 6 to 10, A represents a cylinder of usual construction, preferably having a removable head B , both cylinder proper and the head in the embodiment illustrated having the usual water cooling means. The inlet port in the embodiment illustrated is formed on the head of the cylinder and opens into a cylindrical recess in the head of the cylinder adapted to form a compression space. The exhaust ports 12 and 13 are circumferentially arranged and formed near the end of the cylinder. The passage of 115 motive fluid to both the inlet and exhaust ports is adapted to be controlled by separate cylindrical valve means, turned or rotated by suitable mechanism. In this embodiment separate valve members are provided for 120 each of the ports, the exhaust ports being controlled by a cylindrical valve member or ring C mounted on a seat 14 formed on the interior of the cylinder. In the embodiment 125 illustrated, the upper edge of the valve member C is adapted to abut the inner surface of the head B . Means are provided extending across the joint between the valve member and the cylinder to prevent passage of 130 motive fluid; the means illustrated compris-

ing rings 15 and 16 located in grooves 17 and 18 formed in the edges of the valve member, said rings being normally forced outwardly by springs 19 and 20. The effectiveness of the rings may be further increased by the provision of a groove 21 on the seat 14 to receive the ring 15, and a groove 22 formed on the under surface of the head of the cylinder. The valve member C is provided on its periphery with ports 23 and 24 adapted to register at a determined point in the movement of the member with the exhaust ports 12 and 13, the movement of the valve member being effected by any suitable means, and being oscillatory or reciprocatory as desired. In the embodiment illustrated a stem 25 is shown extending through the end of the cylinder and coaxial therewith and connected to a spider 26 on the valve member, the stem 25 being turned by suitable means, as by a chain 27 and sprocket 28 on the stem. The inlet port is adapted to be controlled through a tubular cylindrical valve member D fitting the cylindrical recess 11 and formed at one point with a slot 27 adapted to register at a given point with the inlet port to permit the passage of the motive fluid into the cylinder. This valve member may be actuated in any suitable way. As illustrated, a sleeve 28 is provided on the valve member encircling the stem 25 and adapted to be turned by means of a sprocket 29 and chain 30. It is apparent, however, that any other suitable mechanism might be provided for actuating the valve member.

As many changes could be made in the above construction, and many apparently widely different embodiments of our invention within the scope of the claims constructed without departing from the spirit or scope thereof, it is intended that all matter contained in the accompanying specifications and drawings shall be interpreted as illustrative and not in a limiting sense.

What we claim as our invention is:

1. An engine cylinder having inlet and exhaust ports located in different planes at different distances from the center and rigidly connected tubular valve means controlling both of said ports, said means each being located adjacent the same end of the cylinder and being movable in a different direction for each port.

2. An engine cylinder having inlet and exhaust ports communicating therewith at one end thereof and being located in different planes at different distances from the center, and rigidly connected tubular valve means adjacent the end of the cylinder with which said inlet and exhaust ports communicate, said valve means being movable in a different direction for each port.

3. An engine cylinder having inlet and exhaust ports in combination with a valve

member adapted when turned in one direction to open the inlet ports and when turned in the opposite direction to open the exhaust ports, said valve member being normally resiliently held in closed position, and means for alternately moving the valve member to opposite sides and permitting the same to swing back to normal position.

4. An engine cylinder having inlet and exhaust ports in combination with a valve member adapted when turned in one direction to open the inlet ports and when turned in the opposite direction to open the exhaust ports, said valve member being normally resiliently held in closed position, means for alternately moving the valve member to opposite sides and permitting the same to swing back to normal position, and means for limiting oscillation after return to normal position.

5. In an internal combustion engine, a cylinder formed at the end with an inlet port opening into a centrally disposed recess and having circumferentially arranged exhaust ports, said recess forming a compression chamber and said inlet and exhaust ports being in different planes, tubular valve means controlling both of said ports and having an independent movement for each port, and means for reciprocating said valve means.

6. In an internal combustion engine, a cylinder formed at the end with an inlet port opening into a centrally disposed recess and having circumferentially arranged exhaust ports, said recess forming a compression chamber and said inlet and exhaust ports being in different planes, tubular valve means controlling both of said ports and being coaxial with the cylinder and formed with slots adapted when the valve means is in a certain position to open the ports, and means for reciprocating said valve means.

7. An internal combustion engine having an exhaust port opening at the end of the cylinder, and an inlet port opening into a cylindrical recess formed at the end of the cylinder of less diameter than the same, tubular valve means mounted on the interior of the cylinder controlling the inlet and exhaust ports, said means comprising a portion of larger diameter controlling the exhaust ports, and a portion of smaller diameter controlling the inlet ports, and means for actuating said valve means.

8. An engine cylinder having inlet and exhaust ports, a valve member adapted when turned in one direction to open the inlet port, and when turned in the opposite direction to open the exhaust port, and spring means for alternately reciprocating the valve member in opposite directions with a quick return motion.

9. In an internal combustion engine, a fixed cylinder, a cylindrical valve rigid

against internal pressure co-axial with the cylinder, inlet and outlet ports in different planes and at different distances from the center, both controlled by the valve, a piston in the cylinder, and means whereby the valve is moved to close the cylinder ports during the compression and explosion cycles of the engine.

10. In an internal combustion engine, a fixed cylinder, a cylindrical valve rigid against internal pressure co-axial with and inside the cylinder, inlet and outlet ports in different planes and at different distances

from the center, both controlled by the valve, a piston in the cylinder, and means whereby 15 the valve is moved to close the cylinder ports during the compression and explosion cycles of the engine.

In witness whereof we have hereunto set our hands in the presence of two witnesses. 20
